JOHN C. WARD, OF QUINCY, MASSACHUSETTS, ASSIGNOR OF ONE-HALF TO WILLIAM J. BIGLEY, OF SOMERVILLE, MASSACHUSETTS.

HOLLOW BODY OF FIBROUS MATERIAL.

1,156,193.

Specification of Letters Patent.

Patented Oct. 12, 1915.

Application filed December 15, 1914. Serial No. 877,437.

To all whom it may concern:

Be it known that I, JOHN C. WARD, a citizen of the United States, residing in Quincy, in the county of Norfolk and State of Massachusetts, have invented an Improvement in Hollow Bodies of Fibrous Material, of which the following description, in connection with the accompanying drawings, is a specification, like characters on the drawings representing like parts.

This invention relates to a hollow body of fibrous material and is herein shown as embodied in a cone for use as a core or support upon which yarn, thread, string or the like is wound to be used in knitting, braiding and like machines. As now commonly constructed, cones for this purpose are made from blanks of paper or like fibrous material in sheet form, which are cut up by suitable dies into blanks, which are folded and have their sides overlapped and cemented together.

The present invention has for its object to provide a paper or other fibrous cone which is stronger and less expensive than those heretofore produced, and upon which the yarn, thread or string can be more easily wound, and from which it may be more easily unwound, as will be described.

To this end, the cone is made from a strip or substantially continuous length of paper or other fibrous material, which is provided on one surface with a layer of adhesive material and is provided on one side or edge with a fold, which is bent over upon the coated surface so as to cover the latter surface for a portion of its width and to leave another portion of the coated surface exposed. The strip thus formed is wound upon a mandrel into the form of a cone, with the uncoated surface of the strip next to the mandrel, and said strip is wound upon the mandrel, so that the exposed coated portion of the outer side of the strip of one convolution will be covered by the upper or folded portion of the next adjacent convolution which is cemented to said coated surface. In this manner a superior cone is formed at a minimum expense, as the cone is composed of a series of convolutions with two thicknesses of paper of one convolution cemented to one layer of an adjacent convolution, which construction gives a stronger cone and forms a series of steps for the thread, yarn or string to engage as the lat-

ter is wound upon the cone, and which facilitates the unwinding of said thread, yarn, etc.

These and other features of the invention will be pointed out in the claims at the end of this specification.

Figure 1 is an elevation of a cone embodying this invention. Fig. 2, a detail of a portion of the strip from which the cone shown in Fig. 1 is made, and Fig. 3, an elevation of a modification to be referred to.

Referring to the drawing, *a* represents a cone of paper or other fibrous material, which is formed from a continuous length or strip *b*, shown separately in Fig. 2. The strip *b* is provided along one edge with a fold 10 which is narrower than the body portion 12 of the said strip, and is cemented to said body portion by adhesive material applied to the outer side of the strip *b* and indicated by the heavy black line 13 in Fig. 2. The coating 13 of adhesive material is applied to the strip *b* before it is folded. The fold 10 being narrower than the width of the body portion 12 leaves the coating 13 exposed on the lower part or half of the strip, and in condition to adhere to the inner surface of said strip, when the latter is helically wound about a mandrel (not shown) to form the cone *a* shown in Fig. 1.

It will be observed, that the cone *a* is composed of a series of convolutions helically arranged, with the folded portion 10 and a part of the body portion 12 of one convolution cemented to the unfolded or lower part of the body portion 12 of the next preceding convolution, so that at each convolution of the cone, the latter is composed of three thicknesses or layers of paper which are cemented together, thereby making a strong and durable cone. A plurality of convolutions of the cone at its top and base may be covered with shellac to impart a finish to the cone, and the latter may be colored at one or both ends to identify the count or number of the yarn, thread or string. The cone may be reinforced at its apex by a cross piece 15, see Fig. 3, which is formed by bending the end of the strip *b* when the latter is started to be wound upon the mandrel, and said cross piece may have its end secured to the first convolution by the shellac.

It will be observed that the series of helical convolutions in the cone form a series of steps 16 which serve to facilitate the wind-

ing of the yarn, etc. upon the cone, when the 5
yarn is first applied, and also facilitate the
unwinding of the yarn when the cone has
been partially unwound or exhausted. This
is especially true when the finer yarns are
used. It will also be observed that there is
no waste of stock from which the cone is
made, and therefore the cost of the cone is
materially reduced.

10 It will be observed that the inner and
outer surfaces of the completed cone are free
from gum or other adhesive, as the inner
surface of the completed cone is formed by
the uncoated inner surface of the convolutions,
while the outer surface of the cone is
formed by the uncoated surface of the fold
10. If desired, the end convolutions may be
mechanically secured together by wire staples
20 or otherwise.

20 In the present instance, I have shown the
invention as embodied in a hollow body in
the form of a cone, which is particularly
serviceable for use in winding machines, but
it is not desired to limit the invention to this
25 particular form of hollow body, as it is evi-
dent that the strip *b* could be wound into cy-
lindrical or other form by substituting a cy-
lindrical or other mandrel for a conical
mandrel.

30 Claims:

1. A hollow body composed of a strip of
fibrous material folded at one edge to form
a folded portion and a body portion of

greater width, and wound into a plurality of
overlapping convolutions which are fastened 35
together.

2. A hollow body composed of a strip of
fibrous material folded at one edge and
wound into a plurality of overlapping con-
volutions which are cemented together with 40
the folded body portion of one convolution
cemented to the unfolded body portion of a
preceding convolution.

3. A hollow body composed of a series of
convolutions of a strip of fibrous material 45
having on one surface a coating of adhesive
material and provided at one edge with a
fold of narrower width than the body portion
of said strip, the folded portion of one
convolution being cemented to the exposed 50
portion of the next preceding convolution by
the adhesive coating thereon.

4. A hollow body composed of a strip of
fibrous material folded at one edge and
wound into a plurality of overlapping con-
volutions, the convolutions between the ends 55
of said body having three layers of fibrous
material cemented together.

In testimony whereof, I have signed my
name to this specification in the presence of
two subscribing witnesses.

JOHN C. WARD.
